JUDSON S. BANFIELD, OF WELLSVILLE, OHIO

CONTINUOUS CALENDAR

Application filed January 18, 1930. Serial No. 421,737.

This invention relates to a continuous calendar, and it has for its primary object to provide a mechanism whereby there may be exposed or displayed automatically and in 5 their properly timed sequence year, month and day indices, together with the calendar dates.

A further object is to provide a calendar mechanism of the character mentioned which 10 may be actuated either electrically or by means of clock mechanism and which normally, except at long intervals, as once in one or more years requires no attention, or manual intervention.

15 In describing the invention in detail, reference is herein had to the accompanying drawings, in which—

Figure 1 is a front elevation of the invention with its enclosing case removed, or indicated in dotted lines;

Figure 2 is an end elevation of the same;

Figure 3 is a top plan view of the same;

Figure 4 is a section on line 4—4, Fig. 1;

Figure 5 is a front elevation on a reduced 25 scale, showing the casing in place and illustrating the manner in which the year, month and day indices and the date in the month are exposed.

Figure 6 is a view similar to Fig. 1, showing in front elevation a modification;

Figure 7 is a top plan view of the same;

Figure 8 is an end elevation of the same; and—

Figure 9 is a front elevation, reduced, with 35 the case in place and showing the manner in which exposure is effected.

Referring to said drawings, 1 designates a suitable form of base which has mounted thereon adjacent to one end a motor enclosed within a suitable casing 2. Said motor may be of any appropriate type and may consist of either an electric motor or a suitable spring-driven clock mechanism, as preferred.

45 Carried by the motor shaft, or rotor 3, outside said casing is a fixed wheel or disk 4 having on its periphery a single tooth 5 adapted, once in each twenty-four hours, to engage a gear wheel 6 fixed on a horizontal 50 shaft 7 which is journaled in suitable sup-

ports, as a part of a supporting frame 8 mounted on said base 1. As herein shown, said gear 6 embodies ten teeth, and, therefore, is actuated to move throughout one-tenth of a revolution in each interval in which it 55 is engaged by the tooth 5 of wheel 4, the arrangement being such that this engagement shall occur at or near midnight of each day. Obviously, however, a greater or lesser number of teeth may be employed in said 60 gear 6, as may be found desirable.

Fixed on said shaft 7 in spaced relation are two identical gear wheels 9 and 10 which are in mesh with gear wheels 11 and 12, respectively, fixed on a countershaft 13 which 65 is journaled in the lower front portion of said frame 8. Said gears 9 and 10 are also in mesh with gears 14 and 15, respectively, fixed on a countershaft 16 which is journaled in the upper front portion of said 70 frame, as shown. Gears 11 and 14, which are of corresponding size and occupy substantially vertically aligned relation, are designed as carriers for one of the lateral edge portions of an endless tape 17, while gears 12 75 and 15, similarly aligned, serve as carriers for the opposite edge portion of said tape.

The tape 17, which is made of appropriate length and width, has printed thereon in consecutive equi-spaced horizontal lines the 80 month-dates 18 of the year, beginning with January 1 and ending with December 31. This tape, the major portion of the length of which is herein shown as normally received within a compartment or well 19 85 provided therefor on the rear portion of the base 1, is advanced by means of the carrier gears 11, 12, 14 and 15, longitudinally aligned perforations 20 provided in the opposite edge portions of the tape being adapted to receive therein the teeth of said gears 90 as the latter rotate forward. The relative sizes of the carrier gears 11, 12, 14 and 15 to the gears 9 and 10 are such that in the movement of said shaft 7 of said gears 95 throughout one-tenth of a revolution induced once in each twenty-four hours, as aforesaid, said carrier gears advance the tape the distance between adjacent month-date lines 18. Thus, when rotary movement 100

throughout one-tenth of a revolution is imparted to said shaft 7, the tape is advanced the distance required to expose through a slot 21 provided therefor in the front wall 5 of the mechanism-enclosing casing 22 the next succeeding month-date line 18.

The tape-receiving well 19 is made of sufficient capacity to accommodate the length of tape which must at all times be contained therein, and the tape, composed of any suitable flexible material, as paper, is preferably scored transversely at suitable intervals between adjacent date lines 18 to facilitate the automatic folding thereof in flat folds of a size adapted to be accommodated by said well, as shown in Fig. 4. A guide-channel 23 is provided by an inclined chute-like extension 24 which leads upwardly and forwardly from the upper end of the well 19 and has its open end located adjacent to the points at which the tape leaves the gears 14 and 15, as shown in Fig. 4. The lowermost of the folds of tape contained in the well rests upon suitable short fingers 25 provided above the bottom of the well in an arrangement which, while serving to support the stored tape, permit the latter to be withdrawn as required in a downwardly and forwardly inclined direction, passing from said well to the under sides of the gears 11 and 12 through a suitable guide-channel 26 provided therefor, as shown.

Also fixed on the shaft 7 at a suitable point is a gear wheel 27 which, preferably, has twenty teeth. Said gear 27 is in mesh with a gear 28 which has fourteen teeth and which is fixed on a countershaft 29. Said countershaft is suitably journaled in an end of the frame 8 and has fixed thereon a wheel 30 which has a suitably wide peripheral surface upon which appear consecutively and in regularly spaced relation designations 31 indicating the days of the week. Thus, as is evident, with each movement of the shaft 7 throughout one-tenth of a revolution, effected once in each twenty-four hours, as hereinbefore described, said wheel 30 is rotated throughout one-seventh of a revolution, thus presenting the next succeeding day designation in a position wherein it is exposed to view through a slot 32 provided therefor in the front wall of the casing 22.

Journalized in the frame 8 at a suitable point is a transverse shaft 33 which has fixed thereon a wheel 34. Said wheel bears on its peripheral face in evenly spaced relation the ten numerals beginning with 1 and ending with 0. A gear 35 having ten peripheral teeth is also fixed on said shaft 33 in a position in which one of its ten teeth is adapted to be engaged once each year by a suitable lug or projection 36 carried by the tape 17, the arrangement of said projection

being such that said once-a-year engagement occurs at midnight on December 31 and effects rotary movement of said shaft 33 and the thereby carried wheel 34 throughout one-tenth of a revolution, thus presenting the next succeeding numeral borne by said wheel in a position wherein it is exposed through a slot or opening 37 provided therefor in the front wall of the casing 22. The numerals carried by said wheel are designed to constitute in succession the final figures of the year dates, the first two figures of which, together with an apostrophe, as shown in Fig. 5, are permanently fixed on the face or front wall of said casing 22 in a position adjacent to said slot 37 so that, in the formation of the year date, they complement the figure exposed through said slot.

To provide for such adjustments as may be rendered necessary from time to time, as in the event that the power mechanism should temporarily fail to function, a key 38 may be engaged with an end of the shaft 7 whereby the latter may be rotated for shifting the tape 17 to the extent required. Also, to provide for adjustment of the wheel 30 relative to the tape-carrying mechanism, the hub 39 of said wheel is detachably engaged with the countershaft 29, the latter having a seven-sided end portion 40 engaged with a correspondingly shaped socket 41 in said hub. A key 42 is provided by means of which said wheel 30 may be withdrawn from said countershaft 29, as to the dotted line position shown in Fig. 3, and then re-seated on said countershaft after having been rotated to properly dispose the wheel-carried week-day designations with respect to the month dates borne by the tape. This last mentioned adjustment is required once each year, except leap year, in cases where the tape carries the date "February 29", or, when such date is omitted, such adjustment will be required once in each leap year.

In the modified construction shown in Figs. 6, 7, 8 and 9 of the drawings, two reels 43 and 44, are substituted for the well 19 hereinbefore described, one of said reels being employed for paying out and the other for receiving the tape 17. Moreover, the tape bears thereon, in consecutive evenly-spaced relation, designations indicating the months, month dates, year dates and days of the week, all closely associated and adapted to be exposed through a single slot or aperture 45 provided in the front wall of the casing. As is apparent, this construction or arrangement obviates the necessity for the employment of the hereinbefore described wheels 30 and 34, together with their associated gears and shafts.

What is claimed is—

1. A casing, a tape having indicia for each of the twelve months thereon, said casing

having a sight opening and having adjacent thereto two numerals and an apostrophe to represent three of four numerals indicating a year, a rotary member having thereon a series of successive numerals to indicate the 5 fourth numeral of each of successive years, means to actuate the tape, and means operable by the tape to actuate said rotary member each twelve months.

10 2. A casing, a tape having indicia for each of the twelve months thereon, said casing having a sight opening and having adjacent thereto two numerals and an apostrophe to represent three of four numerals indicating 15 a year, movable means having thereon a series of successive numerals to indicate the fourth numeral of each of successive years, means to actuate the tape, and means operable by the tape to actuate said movable means each 20 twelve months.

25 3. In a calendar, a frame, a tape having appropriately designated indicia thereon, a well to contain the greater portion of said tape when not in use, a substantially horizontal guide member carried by said well at its upper end and extending forwardly therefrom, a second substantially horizontal guide member carried by said well at its lower end and extending forwardly therefrom, said 30 guides and said well conjointly forming a U structure, a let-off wheel carried by the frame adjacent the free end of the lower guide member and having a portion of its periphery aligned with said lower guide member to 35 unroll tape from the well, a take-up wheel vertically aligned with said first wheel and adjacent the free end of the upper guide member and having a portion of its periphery aligned with said upper guide member to 40 feed the tape into the upper guide member and then into the well, and means disposed substantially within the confines of the U structure to periodically operate the wheels.

45 4. In a calendar, a frame, a tape having appropriately designated indicia thereon, a well to contain the greater portion of said tape when not in use, a substantially horizontal guide member carried by said well at its upper end and extending forwardly therefrom, a second substantially horizontal guide member carried by said well at its lower end, and extending forwardly therefrom, said 50 guide members and said well conjointly forming a U structure, means adjacent the free ends of the guide members and having portions aligned therewith for feeding tape from one guide member vertically and then into the other guide member, and means to 55 periodically operate said tape feeding means 60 disposed substantially within the confines of the U structure.

In testimony whereof I affix my signature.
JUDSON S. BANFIELD.
